US00D921611S

(12) **United States Design Patent** (10) **Patent No.:** **US D921,611 S**
(45) **Date of Patent:** **** Jun. 8, 2021**

(54) **MEDIA PLAYER**

- (71) Applicant: **Sonos, Inc.**, Santa Barbara, CA (US)
- (72) Inventors: **Roland Bird**, Eindhoven (NL); **Roger Swales**, Eindhoven (NL); **Niels van Hoof**, Eindhoven (NL); **Lukasz Natkaniec**, Munich (DE); **Mieko Kusano**, Santa Barbara, CA (US); **Stefan Reichert**, Santa Barbara, CA (US); **Dana Krieger**, Santa Barbara, CA (US); **Tadeo T. Toulis**, Santa Barbara, CA (US); **Mike Chamness**, Santa Barbara, CA (US); **Hilmar Lehnert**, Framingham, MA (US); **Wilfred Wei**, Shanghai (CN); **Wei Hean Liew**, Boston, MA (US)
- (73) Assignee: **Sonos, Inc.**, Santa Barbara, CA (US)
- (**) Term: **15 Years**
- (21) Appl. No.: **29/641,067**
- (22) Filed: **Mar. 19, 2018**

Related U.S. Application Data

- (63) Continuation of application No. 29/558,009, filed on Mar. 14, 2016, now Pat. No. Des. 815,062, which is (Continued)

(57) **CLAIM**

The ornamental design for a media player, as shown and described.

DESCRIPTION

FIG. 1 is a perspective view of a media player.

FIG. 2 is another perspective view.

FIG. 3 is a front view.

FIG. 4 is a rear view.

FIG. 5 is a left view.

FIG. 6 is a right view.

FIG. 7 is a top view; and,

FIG. 8 is a bottom view.

The evenly spaced broken lines shown are included for the purpose of illustrating portions of the media player that form no part of the claim. The dot-dash broken lines represent boundaries of claimed portions of the media player.

1 Claim, 7 Drawing Sheets

US D921,611 S
